[57] CLAIM

The ornamental design for a swivel mount for punching bags, as shown and described.

DESCRIPTION

FIG. 1 is a front elevational view of a swivel mount for punching bags showing my new design, the opposite side being a mirror image of the side shown;
FIG. 2 is a right side elevational view thereof;
FIG. 3 is a bottom plan view thereof;
FIG. 4 is a left side elevational view thereof; and
FIG. 5 is a top plan view thereof.
